UNITED STATES PATENT OFFICE.

ALBERTUS W. McCALMONT, OF PONTIAC, MICHIGAN, ASSIGNOR TO BRISCOE DEVICES CORPORATION, OF PONTIAC, MICHIGAN, A CORPORATION OF MICHIGAN.

VAPORIZER.

Application filed April 11, 1921. Serial No. 460,541.

To all whom it may concern:

Be it known that I, ALBERTUS W. McCALMONT, a citizen of the United States of America, residing at Pontiac, in the county 5 of Oakland and State of Michigan, have invented certain new and useful Improvements in a Vaporizer, of which the following is a specification, reference being had therein to the accompanying drawings.

10 The invention relates to vaporizers for use in connection with carburetors, and it is the object of the invention to obtain a simple construction applicable to any form of internal combustion engine. To this end 15 the invention consists in the construction as hereinafter set forth.

In the drawings:

Figure 1 is a plan view of the vaporizer attachment;

20 Figure 2 is a section through the junction between the carburetor and intake manifold of an internal combustion engine showing the vaporizer in section on line 2—2 of Figure 1;

25 Figure 3 shows a modified construction applied directly to the manifold.

In the construction of carburetors for internal combustion engines the liquid fuel is finely sprayed in the carbureting chamber, 30 but in the further passage through the intake, consolidation of the small particles frequently takes place. Thus there is a tendency for the fine globules of the liquid to coalesce and form larger globules and 35 also to collect upon the surface of the conduit, particularly where there is a change in direction of the current. My improved vaporizer is designed to take advantage of the first spraying of the liquid and to contribute to the vaporization of the same without greatly heating the air. This I have accomplished by the arrangement of a heated surface adjacent to the throttle so as to be 40 directly in the path of the mixture passing from the carburetor particularly where the 45 throttle is partly closed. The heated surface is preferably formed of tubing which is cast into a section of the intake adjacent to the carburetor, said conduit having one end connected to the exhaust manifold for receiving 50 a portion of the exhaust gases therefrom.

With the construction shown in Figure 1, A is a member insertable between the 55 joining flanges of the carburetor and the in-

take manifold, being formed with an aperture B registering with said carburetor and intake and the apertures C for the passage of the clamping bolts. D is a conduit preferably formed of a metal or alloy having a 60 relatively high heat conductivity and which extends through the member A, being preferably cast therein and the latter being preferably a die casting. As shown in Figure 2, a portion of the tubing passing through the 65 gas passage is flattened, as indicated at E, and one side of the tube is adjacent to the wall of the member A. The arrangement is also such that when the member A is inserted between the carburetor F and intake 70 manifold G, the throttle H, when partially closed, will direct the fuel mixture against the tube. Outside of the member A the tube D is of sufficient length to make connection with the exhaust manifold and is provided 75 at its end with a coupling nipple I and union J. The other end of the tube may be formed into a muffler as by closing the end of the same and providing a series of fine apertures K.

The construction as described can be manufactured at very low cost and as the carburetor is always separable from the intake manifold, there is nothing to prevent the insertion of the vaporizer therebetween. 80 If desired, however, the vaporizer may be applied to either the carburetor or the intake manifold, as indicated in the modified construction of Figure 3.

In operation, the portion of the exhaust 90 gases which passes through the tube D will heat the exposed surface of the portion E sufficiently to greatly assist in vaporizing the liquid, but the amount of heating surface is nevertheless so restricted that very 95 little heat is imparted to the air. Consequently, the temperature of the mixture is not greatly elevated.

What I claim as my invention is:

1. In a vaporizer for internal combustion 100 engines, the combination with the intake conduit, of a throttle controlling said conduit, adapted when partly open, to direct the flow primarily along one side of the conduit, a tube extending across the passage of 105 said conduit adjacent to said throttle and adjacent to the side of said passage along which the primary flow is directed in the partly opened position of the throttle, said tube being flattened within the conduit 110

transversely to the flow therethrough, said tube forming a conduit for a heating fluid.

2. In a vaporizer for internal combustion engines, the combination with a sectional intake conduit and a throttle valve in one section thereof adapted to effect a flow of fuel mixture primarily adjacent to one side of said conduit when partly open, of a member interposed between the sections of said
- 10 intake conduit having an opening therethrough registering with the openings in the ends of the adjacent sections, the diameter of said opening being substantially the same

as the diameter of the passages in said sections, and a tube extending through said member having a flattened portion extending across the opening therein, said tube being adapted to receive a heating medium, said flattened portion being disposed near that side of the opening in said member to which the primary flow of mixture is deflected when said throttle is partly open.

In testimony whereof I affix my signature.

ALBERTUS W. McCALMONT.
